VACUUM CLEANER APPLIANCE

Leonard Oren McCracken, North Little Rock, Ark.

Application February 18, 1936, Serial No. 64,553

1 Claim. (Cl. 15—158)

This invention appertains to new and useful improvements in appliances or attachments for vacuum cleaners and more particularly to a novel construction for facilitating the removal of dust and other foreign matter from under low setting pieces of furniture such as upright pianos, davenport ports, bookcases and the like.

The principal object of the present invention is to provide a nozzle construction which can be manipulated under low setting furniture in such a way as to cause agitation of dust or other foreign matter and simultaneous removal by suction of the same.

Another important object of the invention is to provide a nozzle construction of the character stated which can be easily manipulated and which will be efficient and practical in use.

Other important objects and advantages of the invention will become apparent to the reader of the following specification.

In the drawings:

Figure 1 represents a side elevational view of the appliance connected with a vacuum cleaner.

Figure 2 is a top plan view of the nozzle.

Figure 3 is a bottom plan view of the nozzle.

Figure 4 is a fragmentary side elevational view of the nozzle.

Figure 5 is a fragmentary side elevational view of the nozzle with a portion of the reinforcing band removed.

Figure 6 is a fragmentary side elevational view of the nozzle with the brushes removed.

Figure 7 is an enlarged cross sectional view on line 7—7 of Figure 4.

Figure 8 is a fragmentary transverse sectional view (enlarged) taken substantially on line 8—8 of Figure 4.

Figure 9 is a fragmentary enlarged sectional view taken substantially on line 9—9 of Figure 2.

Figure 10 is a fragmentary top plan view of a modified form of the invention.

Figure 11 represents a cross sectional view taken substantially on line 11—11 of Figure 10.

Referring to the drawings wherein like numerals designate like parts, it can be seen that the device is an elongated narrow and thin or shallow conduit 5. As a matter of fact the same can be referred to as substantially flat and is provided

with a removable cap 6 at one end. This cap is removable so that an extension can be placed on the nozzle, or simply to serve as a closure as shown in Figure 2. The opposite end of the nozzle 5 is provided with an inclined neck portion 7.

The bottom side of the nozzle 5 adjacent the

free end thereof is provided with a pair of suction ports 8.

Brushes are provided for the free end and sides of the nozzle 5 and each of these brushes consists of a strip of wood 9 secured to the opposite longitudinal edge portions of the nozzle by passing bolts 10 transversely through the nozzle 5 with the heads 11 and the nuts 12 countersunk in the strip 9, it being seen that bristles 13 depend from the strips 9 a short distance below the bottom surface of the nozzle 5 as in the manner substantially shown in Figure 7. The free end of the nozzle 5 has a brush section 14 which is connected to the adjacent end of the strip 9.

If desired, fastening means in the form shown in Figure 11, can be adopted and in this form reference characters 9a—9a represent the brush strips corresponding to the strips 9—9 and 13a are the bristles depending therefrom. In securing these strips 9a in place, metallic strips 10a are disposed over and under the nozzle 5 as well as the top and bottom sides of the strips 9a and bolts 15 equipped with nuts 16 are passed vertically through the strips 9a and through the corresponding ends of the metallic strips 10a—10a, thus clamping the strips 9a firmly in place between the projecting end portions of these metallic strips 10a.

In both forms of the invention, a metallic band 17 extends entirely along the outermost sides of the strips 9 and end brush 14, so as to protect these strips and brush 14 against marring and damage when knocked against furniture and other objects. This band 17 is secured in place by small screws 18.

Numerals generally refer to the usual vacuum cleaner construction of conventional make on which the adapter 20 is located to which the hose 21 is connected. This hose extends to an elongated stiff metallic tube 22 which can serve as a handle if the operator desires. The remaining end of this tube 22 is connected by a short resilient tube 23, secured to the neck 7 and the tube 22 by clamps 24. Thus, sufficient universal action of the nozzle 5 is obtained by the connection 23 when the tube 22 is being used as a handle.

Thus it can be seen, that this appliance can be used for removing dust and other foreign matter from under davenport, upright pianos, low setting bookcases and other pieces of furniture, as well as under the edge portion of carpets, rugs and other floor pieces.

While the foregoing specification sets forth the invention in specific terms, it is to be understood

that numerous changes in the shape, size and materials may be resorted to without departing from the spirit and scope of the invention as claimed hereinafter.

5 Having thus described the invention, what is claimed as new is:

An appliance for vacuum cleaners comprising an elongated shallow narrow nozzle, a removable closure at one end of the nozzle, elongated members provided along the longitudinal edges of the

10

nozzle, a transversely extending member across the outer end of the closure, said elongated members and transverse member being provided with depending bristles, and a continuous retaining band secured to the outsides of the said elongated members and transverse member for holding the same intact with the nozzle and the closure against displacement.

LEONARD OREN McCACKEN. 10
